LINEAR ACCELERATOR

Stirling A. Colgate, Livermore, Calif., assignor to the United States of America as represented by the United States Atomic Energy Commission

Application July 22, 1955, Serial No. 527,892

3 Claims. (Cl. 315—5.41)

The present invention relates to a linear accelerator for charged particles and, more particularly, to a spiral beam linear accelerator.

With the increased utilization of accelerators for charged particles as tools in the field of nuclear physics for research purposes and in the field of production of radioactive isotopes, such accelerators must be capable of handling beams of charged particles having larger current intensities than has heretofore been achieved and with a higher degree of efficiency. The linear type of particle accelerator is inherently capable of handling higher values of current than cyclotrons, betatrons, or synchrotrons because the latter depend upon revolving charged particles an enormous number of times while increasing the energy thereof and thereby increase the possibility of losing particles with the resultant decrease in the value of the output current. Another disadvantage arises from the difficulty in removing the accelerated beam out of the accelerator apparatus. With a linear accelerator of the Sloan-Lawrence type the charged particles are increased in energy by a series of favorable electric fields disposed along a linear path and a given particle energy can be readily achieved in a much shorter length of path.

In the past, it has been found that a foremost problem has prevented the achievement of a stable focussed beam with a linear accelerator in that beam instability has arisen from the defocussing effect of the accelerating electric fields and from the mutual repulsion of the charged particles within the beam (sometimes referenced as space charge defocussing). The problem of focussing has been met in one type of linear accelerator (Alvarez, U. S. Patent No. 2,545,595, March 20, 1951) by the use of focussing foils; however, such foils tend to decrease the efficiency of the accelerator.

The above-mentioned difficulties and disadvantages of previously-known linear accelerators are overcome with the present invention by providing a radial electric field transverse to the accelerating electric fields and angularly introducing the beam of particles into the fields. The result of the foregoing is to achieve a beam which spirals about the axis of the acceleration path. The combination of the electric fields and angular motion of the beam cooperate to provide stability and focussing.

It is therefore an object of the present invention to provide a new and improved linear accelerator.

Another object of the invention is to provide a new method and apparatus for focussing a beam of charged particles during acceleration.

A further object of the invention is to provide a linear accelerator having a spiralling beam.

Still another object of the invention is to provide a linear accelerator having means to neutralize the effects of space charge.

Another object of the invention is to provide a linear accelerator wherein charged particles are angularly introduced into a series of accelerating fields substantially parallel to the acceleration path and radial fields transverse to such path.

Other objects and advantages of the invention will be apparent in the following description and claims considered together with the accompanying drawing which is a schematic cross-section of the invention.

- 5 Referring to the drawing in detail, there is provided an elongated vacuum-tight tank 11 having conventional evacuating means (not shown) communicating therewith. Disposed at one end of the tank 11 is a conventional ion source 12 which provides a beam of charged particles 13
10 having a high value of current. The ion source 12 may readily be mounted within the tank 11 or, as illustrated, disposed externally to inject the beam 13 through a communicating tube 14. A plurality of hollow and open-ended drift tubes 16 is disposed coaxially within the tank
15 11. Such drift tubes 16 are of graded lengths with the shorter disposed adjacent to the ion source end of the tank 11 and are spaced-apart along the axis to provide gaps of increasing length with the shorter gap occurring at the ion source end of the tank.
20 A first conductor 17 is disposed parallel to the axis of the tank 11, in insulated relation with respect to the tank and is connected electrically to alternate drift tubes 16 commencing with the drift tube closest to the ion source end of the tank (i. e., the odd numbered drift tubes). A second conductor 18 is similarly disposed parallel to the axis of the tank 11, in insulated relation with respect to the tank, and is electrically connected to alternate drift tubes 16 commencing with the second closest drift tube to the ion source end of the tank. The
25 30 mountings (not shown) of the two conductors 17, 18, as well as the two conductors and the electrical connections, may readily support the drift tubes 16 within the tank 11.
To provide suitable acceleration of charged particles injected into the opening of the first drift tube 16, a high frequency alternating voltage is impressed upon the first and second conductors 17, 18 from a radio-frequency power supply 21. Since such accelerating voltage has a high frequency, the feeder system comprises two stem conductors 22, 23 electrically connected at a point of
35 40 zero voltage by a shorting bar 24. Output terminals 26, 27 of the radio-frequency power supply 21 are respectively coupled to proper impedance points on the stems 22, 23 by capacitors 28, 29 so that the combination of the stems, first and second conductors 17, 18 and drift tubes 16 provide a resonant system at the frequency of the radio-frequency power supply. With the ion source 12 operating to inject a beam of charged particles through the drift tubes 16 along the axis of the tank 11 and with a target 31 disposed to receive the accelerated beam at the end of the tank opposite the position of the ion source, the structure thus far described and the operation thereof is that of a conventional linear accelerator.
45 50 55 To overcome the aforementioned difficulties and disadvantages inherent in conventional linear accelerators, structural modifications and additions are required which will be set forth hereinafter. An elongated electrode 32, having a substantially small cross-section in comparison to that of the drift tubes 16, is extended through the drift tubes along the axis of the tank 11. To impress a suitable voltage upon such elongated electrode 32, a conventional high voltage direct current power supply 33 is provided with one terminal 34 connected to ground and another terminal 36 connected to the electrode. A second conventional direct current power supply 37 is connected with a terminal 38 tied to the shorting bar 24 of the stem conductors 22, 23 and another terminal 39 connected to ground. Such second power supply 37 provides a source of bias voltage to the drift tubes 16 and, together with the high voltage power supply 33, establishes a uniform radial electric field within each of the drift tubes 16. With
60 65 70

the elongated electrode 32 installed; as stated above, the ion source 12 is disposed in such manner as to inject an ion beam 13 angularly into the radial electric field of the first drift tube 16; that is, the ion source is disposed off-center with respect to the center of the end wall of the tank 11 and the communicating tube 14 is angularly extended through the end wall.

To accelerate positively charged particles the negative terminal of the high voltage power supply 33 is connected to the elongated electrode 32 and the positive terminal of such power supply is grounded. A low value of bias voltage is provided to the drift tubes 16 by the connection of the power supply 37 to the shorting bar 24 of the stem conductors 22, 23. It will be readily apparent then that a uniform radial electric field is established between the elongated electrode 32 and the drift tubes 16. It is well known that charged particles moving along a path transverse to an electric field are acted upon by a force which causes same to transverse a curved path. Thus by injecting particles from the ion source 12 as a beam along a path which has a component parallel to the electric field and also a component transverse to the field, the beam is forced to follow a spiral path because of the attractive force established toward the elongated electrode 32. The particles of such beam are also acted upon by a centrifugal force which is a repulsive force away from the elongated electrode 32. When the attractive force and the repulsive force acting upon the particles are balanced there exists a stable "potential well" which confines the charged particles to a substantially constant spiral path for the length of the accelerator. It can be readily proven mathematically that the motion of the particles parallel to the elongated electrode 32 is independent of the established "potential well" so that accelerating electric fields disposed along the spiral path do not disturb the "potential well."

Thus, in operation the ion source 12 introduces charged particles in a beam 13 with an initial velocity at an angle to the direction of the electric field between the elongated electrode 32 and the drift tubes 16. An angular momentum is then imparted to the particles of the beam by the radial electric field and the beam follows a constant spiral path. As the charged particles of the beam 13 approach the gap between the first and second drift tubes 16, nearest the ion source 12, the radio-frequency power supply 21 impresses an increasing electric field between the two drift tubes to increase the energy of the particles during traversal of the gap. Because of the strong forces acting upon the particles to maintain the beam in the "potential well," the substantially lesser defocussing forces at the gap produced by the accelerating electric field are not effective to disrupt the spiral path. Thus phase stability, as well as particle focussing, are maintained during the acceleration action. While the voltage of the radio-frequency power supply 21 is reversing polarity the particles drift through the second drift tube 16 and reach the following gap when an accelerating electric field is presented. The foregoing action continues successively while the beam 13 spirals in the "potential well" between the elongated electrode 32 and the drift tubes 16 until the final gap has been crossed and the target 31 reached. Since the beam 13 has a spiral configuration about the elongated electrode 32, the presence of the elongated electrode at the center of the beam introduces a charge of opposite polarity to that of the particles and thereby neutralizes the effects of space charge defocussing.

In accordance with the foregoing, it has been found that a beam of protons is accelerated to provide a stable well-focussed output beam with higher energy and with substantially no loss of particles under the following conditions:

1. Diameter of drift tubes 16: 6 inches.
2. Diameter of elongated electrode 32: $\frac{3}{4}$ inch.
3. Frequency of radio-frequency power supply 21: 12.6 megacycles per second.

4. Ratio of gap between drift tubes 16 to length between center-lines of successive gaps: 0.2.
5. Constant voltage gain per gap: 10 kilovolts.
6. Voltage between elongated electrode 32 and drift tubes 16: 50 kilovolts.
7. Injection voltage: 25 kilovolts.
8. Twelve drift tubes 16 giving a final energy of 120 kilovolts.

It will be readily apparent from the above example, that, by a mere alteration of the values set forth, a much greater final energy is attainable. Also, because of the necessary increased lengths of the final drift tubes in an accelerator having a plurality of drift tubes, a second accelerator section may be used with a higher value of acceleration voltage frequency to further accelerate the beam of particles. Such use of two accelerator sections is simplified because of the great stability and focussing of the beam at the output of the first section and permits the use of shorter lengths of drift tubes at the high energy end of the accelerator than is otherwise possible.

While the salient features of the present invention have been described in detail with respect to a single embodiment, it will be apparent that numerous modifications may be made within the spirit and scope of the invention and it is therefore not desired to limit the invention to the exact details shown and described except insofar as they may be defined in the following claims.

What is claimed is:

1. In a linear accelerator, the combination comprising a vacuum-tight tank, a plurality of drift tubes mounted in coaxial spaced-apart relation along a linear path in said tank, means connected to said drift tubes to provide a plurality of radio frequency accelerating electric fields along said linear path, an elongated electrode extended through said drift tubes, direct current power supply means connected between said electrode and said drift tubes to provide a radial electric field, and means disposed at one end of said tank for injecting particles having an angular momentum into said radial electric field and said particles having a charge attracting same toward said electrode, whereby said particles are accelerated in a substantially constant spiral about said electrode.

2. In a linear accelerator, the combination comprising a vacuum-tight tank, a plurality of drift tubes mounted in coaxial spaced-apart relation along a linear path, a source of radio-frequency accelerating voltage connected between successive pairs of said drift tubes to provide a plurality of accelerating electric fields along said linear path, an elongated electrode mounted coaxially with respect to said drift tubes along said linear path, direct current power supply means connected with a negative terminal thereof to said electrode and a positive terminal thereof to said drift tubes to provide a uniform radial electric field in each of said drift tubes, and particle injecting means mounted at one end of said tank in angular relation with respect to said radial electric field and disposed to inject positively charged particles into said radial electric field with an angular momentum, whereby particles are accelerated in a substantially constant spiral about said electrode.

3. In a proton linear accelerator, the combination comprising a vacuum tight tank, a plurality of drift tubes coaxially mounted in spaced-apart relation along a linear path, a source of radio-frequency accelerating voltage connected between successive pairs of said drift tubes to provide a plurality of accelerating electric fields along said linear path, an elongated electrode mounted coaxially with respect to said drift tubes along said linear path, direct current power supply means having a negative and a positive terminal with said negative terminal connected to said electrode and said positive terminal connected to said drift tubes, and a proton ion

source mounted angularly at one end of said tank to provide a beam of protons directed into the region between said electrode and drift tubes with an angular momentum, whereby said protons are accelerated in a substantially constant spiral about said electrode.
